UNITED STATES PATENT OFFICE.

WILLIAM KEATING, OF NEW YORK, N. Y.

SAFETY DEVICE FOR ELEVATORS.

1,099,181.

Specification of Letters Patent.

Patented June 9, 1914.

Application filed June 4, 1913. Serial No. 771,588.

To all whom it may concern:

Be it known that I, WILLIAM KEATING, a citizen of the United States, and a resident of the city, county, and State of New York, have invented certain new and useful Improvements in Safety Devices for Elevators, of which the following is a specification, reference being had to the drawing, forming a part thereof.

10 My invention relates to safety devices for elevators and the like, and particularly to such as are adapted to prevent the starting of the car when the car door is open.

One object of my invention is to provide 15 a safety device of the class above indicated that shall be effective in operation and comprise a few simple parts.

Another object is to provide a device 20 which will automatically prevent not only the starting of the car when the door is open, but also the opening of the door when the starting lever is moved out of its central "off" or "stop" position.

Other objects and advantages will be set 25 forth hereinafter.

I will describe my invention in the following specification and point out the novel features in appended claims.

Referring to the drawings,—Figure 1 is 30 a partial elevation of an elevator car equipped with the safety device of my invention. Fig. 2 is an interior elevation at right angles to Fig. 1 which shows the elevator controller and a portion of the safety device. A sectional plan view of one corner of the elevator car is shown in Fig. 3, the safety device being shown in the position which it is adapted to occupy when the car door is open. Fig. 4 is a view corresponding to Fig. 3 except that the safety 40 device is shown in the position which it occupies when the car door is closed.

Like characters of reference designate corresponding parts in all the figures.

45 10 is an elevator car having a door 11 and a controller lever 12, the lower part of which is covered by a casing 13. The controller lever 12 is adapted to swing backward or forward from a central "off" position to drive the car in an upward or downward direction in a well known manner. Rotatably supported over the controller 12 is a shaft 20 which forms a part of my improved safety device. Secured to one end of the 50 shaft is a crank arm 21 which is connected to the door 11 by a link 22.

The arrangement of parts is such that a 55 rotative movement of the shaft 20 is produced as the door is opened or closed. A locking bar 24 having a notch 25 is secured 60 to the shaft 20 intermediate its ends. This bar may be integral with the shaft or secured to it in any suitable manner. It is so arranged that it lies in a substantially vertical 65 plane and does not interfere with the free operation of the control lever 13 when the door is closed, but the lever 21 and the link 22 are so proportioned that it is swung into a horizontal plane when the door is opened. The notch 25 is arranged to receive the 70 control lever 12 in its central "off" position and consequently the controller is locked in this position when the door is open.

The device obviously not only prevents 75 the movement of the lever out of its "off" position when the door is open, but also prevents the opening of the door when the lever is out of its "off" position. Therefore, the car cannot be started in either direction until the car door is shut.

If desired the slot may be of sufficient 80 width to allow the operator to give an extremely slow movement to the car so that he may overcome any creeping of the car or may bring it more exactly to the landing 85 level. The locking bar is also so arranged that the car door cannot be opened unless the control lever is returned to its "off" position as a tendency to open the door will be opposed by the locking bar 24 pushing 90 against the control lever which is held against any outward movement by its pivot and by the casing 13.

As shown in Fig. 3, one end of the shaft 95 20 may extend through the inside partition wall of the car and the crank 21 and link 22 located beyond this wall or between the inner and outer walls of the car if the car has double walls. The door may comprise a collapsible grating as shown in Fig. 1 or 100 may slide into its casing or into the car walls.

Variations in size and arrangement of 105 parts may be effected within the spirit and scope of my invention and I desire that only such limitations be imposed as are indicated in the appended claims.

What I claim is:

1. In an elevator, the combination with a car, a controller therein having a movable lever adapted to be moved, in one plane in 110 one direction or the other from an interme-

diate position, and a door movable in a plane at an angle to the plane of lever movement, of a rotatable shaft adjacent to the control lever and parallel to its plane of movement, 5 a locking bar secured to the shaft and having a notch, a crank arm secured to the shaft and a link connecting the outer end of the crank arm to the door, whereby the opening of the door swings the locking bar to prevent the 10 movement of the control lever out of its intermediate position.

2. In an elevator, the combination with a car, a controller therein, having a movable lever adapted to be moved in one direction or the other from an intermediate "off" 15 position, and a door, of a rotatable shaft adjacent to the control lever and parallel

to its plane of movement, a locking bar secured to the shaft and having a central notch, a crank arm secured to the shaft and 20 a link connecting the outer end of the crank arm to the door whereby the closing of the door swings the locking bar out of the path of travel of the control lever and whereby the movement of the control lever out of its 25 central "off" position prevents the opening of the door.

In witness whereof, I have hereunto set my hand this 3rd day of June, 1913.

WILLIAM KEATING.
